UNITED STATES PATENT OFFICE.

ROBERT J. ALBRECHT, OF RACINE, WISCONSIN, ASSIGNOR TO HAMILTON-BEACH MFG. CO., OF RACINE, WISCONSIN, A CORPORATION OF WISCONSIN.

SPINDLE MOUNTING.

Application filed February 21, 1922. Serial No. 538,213.

To all whom it may concern:

Be it known that I, ROBERT J. ALBRECHT, a citizen of the United States, residing at Racine, county of Racine, and State of Wisconsin, have invented certain new and useful Improvements in Spindle Mountings, fully described and represented in the following specification and the accompanying drawings, forming a part of the same.

10 This invention relates to spindle mountings, and particularly mountings for vacuum cleaner brush-spindles.

In certain types of vacuum cleaners, the brush spindles have their ends mounted in 15 open, downwardly extending pockets or notches, the spindle being normally held in place by the pull of an elastic belt which drives the spindle from the fan shaft. It is sometimes necessary to remove this belt 20 from its drive pulley or shaft so that its pull on the spindle is released. Inconvenience often results in that the spindle is free to drop out of the mounting pockets or notches.

It is the principal object of the present invention to provide spindle-retaining means 25 such that spindles mounted as above described are normally but removably held in place, even when the tension of the belt is released.

30 With this general object in view the invention consists in the combinations, details of construction, and arrangements of parts which will first be described in connection with the accompanying drawing and then 35 more particularly pointed out.

In the drawing:

Fig. 1 is a front end view, with parts in vertical section, of a portion of a vacuum cleaner constructed in accordance with the 40 invention;

Fig. 2 is a vertical sectional view (enlarged) of one end of the cleaner nozzle;

Fig. 3 is a sectional view taken on the line 3-3 of Fig. 2;

45 Fig. 4 is a face view of the spindle retainer removed; and

Fig. 5 is an edge view thereof.

Referring to the drawing, there is shown by way of illustration, a part of a vacuum 50 cleaner comprising a fan casing 21, and a nozzle 22 having a suction mouth 23. Associated with this suction mouth so as to engage the surface to be cleaned, is a brushing element comprising a spindle 24 provided 55 with suitable brush bristles 25. There is

provided at each end of the nozzle a mounting for the ends of the spindle. At least one of these mountings has an open, downwardly extending pocket or notch in which the spindle end is adapted to seat, and in constructions embodying the invention to the best advantage, these end mountings have several pockets of different depth for a purpose hereinafter explained. Although capable of various constructions, in the form here illustrated, secured to each end of the nozzle, above the suction mouth, by screws 26, is an angularly movable bracket 27 which may be made of fibre or other suitable material. Each bracket 27 has formed in its periphery 60 a plurality of U-shaped notches or open pockets 28 of different depth, the bracket being so positioned that one of its notches or pockets opens downwardly.

While the spindle ends which are to seat 75 in the open pockets may have various forms and constructions, in the exemplification here illustrated, they are in the form of journal boxes. As shown, the spindle 24 has at 80 each end a journal 29 formed by a pin set in the spindle. The journal box shown as an example, comprises a casing 30 closed at its outer end and trough shaped in cross section. The apex of the trough constitutes a bearing 85 portion 31 for the journal 29 and the flaring portion 32 of the casing 30 provides a chamber for holding a lubricating element 35. In the present embodiment, the casings 30 have cap members 34 that slip over the spindle as 90 shown in Fig. 2.

The combined journal box and cap member being placed on the spindle, becomes, in effect, part of the spindle, the journal box constituting the spindle end that is to be seated in the pocket of the mounting bracket. 95 The spindle is positioned for use by inserting its ends in the bottom notches or pockets of the brackets, as appears in Fig. 3.

The purpose of the several notches or pockets is to enable the brushing element to 100 be adjusted to compensate for wear. When the bristles are new, the mounting brackets are set with the deepest notches in position for use. After the bristles of the brush have 105 become worn, the spindle may be removed and the bracket turned to place less deep notches in the bottom position. Thus the spindle is mounted nearer to the plane of the suction mouth to compensate for the 110 wear of the bristles.

The spindle may be normally held in position by the pull of an elastic driving belt. To this end, as here shown as an example, the spindle has a central pulley 36 over which runs a belt 37 of rubber or other suitable material. This belt is driven by a pulley 38 on a drive shaft 39 which may conveniently be an extension of the fan shaft. The pull of belt 37 on the spindle draws the 10 spindle ends, in this instance the journal boxes 30, up into the notches or pockets and holds the spindle in place.

As before stated, the belt is sometimes removed from the driving position so that its 15 pull on the spindle is released. To keep the spindle in position even upon release of the belt, there is provided a retainer device for preventing the spindle end from dropping out of its pocket, this device being dis- 20 placeable to permit removal of the spindle when desired. This may be accomplished, for example, by a displaceable loop arranged to pass below the spindle. Although capable of various constructions, in the present em- 25 bodiment, the retainer device comprises for each end of the spindle, a plate 40 of thin, spring metal having a spring loop 41 bowed outwardly or offset therefrom, as appears, for example, in Fig. 5. The plate 40 is mounted on the pin 26, being clamped be- 30 tween the bracket 27 and the end wall of

the nozzle. So mounted, the offset loop 41 is in a position to pass below the end of the spindle, thus acting as a retaining clip to prevent the spindle from dropping out 35 should the pull of the belt be released.

The spindle is, however, readily removed and inserted when desired. The spring loops 41 are easily pushed back to permit the spindle ends to pass or a substantial pull on the 40 spindle causes displacement of the loops 41 from retaining position. Similarly, in re- inserting the spindle, the loops 41 are easily displaced to permit the spindle ends to be seated in their pockets, whereupon the loops 45 again spring into retaining position.

What is claimed is:

In a vacuum cleaner, in combination with a nozzle having a suction mouth, a brush spindle, a spindle mounting associated with 50 the nozzle and having an open, downwardly facing pocket in which the spindle end is adapted to seat, and a plate associated with said spindle mounting, having an offset spring loop arranged to pass below the 55 spindle for normally preventing the spindle from dropping out and displaceable to permit removal of the spindle.

In testimony whereof, I have hereunto set my hand.

ROBERT J. ALBRECHT.
